(57) **CLAIM**

An ornamental design for a base mount, as shown and described.

DESCRIPTION

FIG. 1 is a front perspective view of a first embodiment of a base mount;

FIG. 2 is a front elevational view thereof;

FIG. 3 is a rear elevational view thereof;

FIG. 4 is a right-side elevational view thereof;

FIG. 5 is a left-side elevational view thereof;

FIG. 6 is a top view thereof;

FIG. 7 is a bottom view thereof;

FIG. 8 is a bottom perspective view thereof;

FIG. 9 is a front perspective view of a second embodiment of a base mount;

FIG. 10 is a front elevational view thereof;

FIG. 11 is a rear elevational view thereof;

FIG. 12 is a right-side elevational view thereof;

FIG. 13 is a left-side elevational view thereof;

FIG. 14 is a top view thereof;

FIG. 15 is a bottom view thereof;

FIG. 16 is a bottom perspective view thereof;

FIG. 17 is a front perspective view of a third embodiment of a base mount;

FIG. 18 is a front elevational view thereof;

FIG. 19 is a rear elevational view thereof;

FIG. 20 is a right-side elevational view thereof;

FIG. 21 is a left-side elevational view thereof;

FIG. 22 is a top view thereof;

FIG. 23 is a bottom view thereof; and,

FIG. 24 is a bottom perspective view thereof.

The broken lines shown as dashed lines are for the purpose of illustrating unclaimed structure, and form no part of the claimed design.

The broken lines shown as dash-dot lines define the bounds of the claimed design and form no part thereof.
